UNITED STATES PATENT OFFICE

ARTHUR E. MILLER, OF MILWAUKEE, WISCONSIN, ASSIGNOR TO CHAIN BELT COMPANY, OF MILWAUKEE, WISCONSIN, A CORPORATION OF WISCONSIN

VEHICLE BODY FOR TRANSPORTING MIXED CONCRETE

Application filed April 20, 1929. Serial No. 356,771.

This invention relates to vehicle bodies for transporting mixed concrete and the like and has for one of its objects to provide a body of this character which will be simple in construction, comparatively inexpensive to manufacture and more efficient in use than those which have been heretofore proposed.

There is a well developed tendency in the concrete art at the present time toward the mixing of the concrete at a central plant from which it is transported by motor trucks or other similar vehicles to the point of use. It has been found, however, in actual practice that where so called "wet mixes" are used, (that is, where the concrete contains a relatively large amount of water in proportion to the aggregates so that the mixture is rather thin,) the said aggregates have a tendency to settle during transportation, leaving the water and cement floating upon the top. It is therefore desirable before dumping the concrete at the point of use, to remix the ingredients; and various types of apparatus have been proposed whereby such remixing may be accomplished just prior to the dumping, or whereby the concrete is more or less continuously agitated during transportation to prevent the segregation of the materials.

The present invention has for its primary object the provision of a special type of vehicle body which will facilitate the remixing of concrete materials which have separated, as above described, just prior to their being dumped at the point of use.

A further object of the invention is to provide a vehicle body which is rotatably mounted upon the chassis of the vehicle in such a manner that its center of gravity lies without the axis of rotation whereby the body may be said to be rendered pendulous or unbalanced so that the concrete may be transported with the center of gravity of the body and contents elevated above the lowest position which it may ever assume, and upon reaching the point of use by releasing a simple holding means the body and

contents may be automatically rotated through the tendency of the center of gravity to assume said lowest position.

With the above and other objects in view which will appear as this description proceeds, the invention consists in the novel details of construction and combinations of parts more fully hereinafter disclosed and particularly pointed out in the appended claims.

Referring to the accompanying drawings forming a part of this specification in which like reference characters designate like parts in all the views:

Figure 1 is a side elevational view of a motor vehicle provided with one form of a body constructed in accordance with the present invention;

Figure 2 is a transverse sectional view taken approximately on the plane indicated by the line 2-2 of Fig. 1 looking in the direction of the arrows;

Figure 3 is a fragmentary perspective view showing the means of locking the rotating body in transporting position; and

Figure 4 is a view similar to Fig. 2 showing a slightly modified form of body.

In the said drawings 10 indicates generally a motor vehicle having a chassis frame 11 upon which is pivotally mounted as at 12, a body supporting frame 13. Any suitable means such as the power operated hoist 14 may be provided for tilting the frame 13 about the pivot 12 to dump the contents of the vehicle body.

As shown in Figs. 1 and 2 the body constituting the present invention comprises a closed elongated metal or other shell 15 which is surrounded by a pair of rings or tracks 16 which rest upon supporting rollers 17 carried by the tilting frame 13.

As shown in the said figures the body is not truly cylindrical, the lower portion thereof as viewed in Fig. 2 being deformed as at 18 whereby the center of gravity of the body will be shifted out of the axis of rotation designated by the numeral 19. For illustrative purposes it has been assumed that the center of gravity has been raised in Fig. 2 to the point indicated by the numeral 20.

The said body may be provided with a filling opening or hatch 21 which is normally closed by a hatch cover 22 such opening being preferably located in the arcuate 5 side wall of the body, and a discharge opening or hatch 23 is also provided in the end wall leading to a discharge chute 24 which is normally closed by a cover plate 25. As will be clear from the drawings, these 10 hatches are displaced from the axis of rotation of the body in substantially the plane of the displacement of the center of gravity.

For holding the body in the transporting position (which is that shown in Figs. 1 and 15 2 with the center of gravity 20 elevated) any suitable mechanism may be provided, such for example as illustrated in detail in Fig. 3. This latch as here shown comprises a bracket 26 having a notch or recess 27 20 which is adapted to receive the toe 28 of a lever 29 which is pivoted as at 30 in a suitable bearing 31. A spring 32 may be provided to normally hold the lever in the position shown in the drawings.

25 In use the body will be positioned as shown in Figs. 1 and 2 by either power or manual operation of the chain 33 which engages a sprocket 34 carried by the body 15 whereupon the hatch cover 22 will be opened and the body filled with mixed concrete. The hatch cover 22 is then closed, after which the vehicle is driven from the central mixing plant to the point of use during which time the larger aggregates may settle 35 to the bottom of the body. Upon arriving at the point of use the operator will raise the lever 29 thereby withdrawing its toe 28 from the recess 27 of the bracket 26 whereupon, the tendency of the center of gravity 20 to seek its lowest position will result in an automatic movement of the body through 40 an arc of substantially 180° thereby bringing the heavier aggregates to the top and providing a remixing of the concrete before 45 discharge. The cover 25 of the discharge chute is then opened and the body tilted by means of the hoist 14 thereby discharging the contents.

The body may obviously take various 50 cross sectional shapes, as for example, that shown in Fig. 2 wherein the distorted portion is corrugated, or that shown in Fig. 4 wherein the lower walls are substantially straight as indicated at 38. While the particular shape of the body may have some 55 effect upon the remixing action it is not wished to be limited to any particular shape since the primary principle involved is that of a closed body in which the center of gravity lies without the axis of rotation and any 60 cross sectional shape may be employed which will produce such a construction.

It is obvious that those skilled in the art 65 may vary the details of construction as well as the precise arrangement of parts without

departing from the spirit of the invention and therefore it is not wished to be limited to the above disclosure except as may be required by the claims.

What is claimed is:

1. In a vehicle for transporting mixed concrete and the like, a chassis; and an unbalanced load receiving body rotatably mounted on said chassis, having a hatch displaced from the axis of rotation in substantially the plane of displacement of the center of gravity of the body. 70

2. In a mobile vehicle for transporting mixed concrete and like mixtures embodying segregatable constituents of different specific 80 gravities, a chassis; a closed receptacle for receiving said mixture freely rotatably mounted on said chassis with its center of gravity displaced from its axis of rotation; and means for releasably holding said receptacle during transport with the combined center of gravity of the receptacle and contents when substantially completely filled above the axis of rotation, whereby, upon

release of said holding means prior to discharge, said receptacle and contents may be automatically inverted through the action of gravity to produce a redistribution of the heavier settled constituents of the mixture throughout the lighter constituents thereof. 90

3. In a mobile vehicle for transporting mixed concrete and like mixtures embodying segregatable constituents of different specific gravities, a chassis; a closed unbalanced receptacle having circular trackways freely 100 rotatably mounting it on said chassis with its center of gravity displaced from its axis of rotation; and a latch for releasably holding said receptacle during transport with the combined center of gravity of the receptacle and its contents when substantially completely filled above the axis of rotation, whereby, upon release of said latch prior to discharge, said receptacle and contents may automatically invert themselves through the action of gravity to produce a remixing of the constituents of the mixture. 105

4. In a mobile vehicle for transporting mixed concrete and like mixtures embodying segregatable constituents of different specific gravities, a chassis; a closed elongated receptacle of irregular substantially semi-circular cross section rotatably pendulously mounted on said chassis; and a latch for releasably holding said receptacle and its contents during transport with the heavier portion elevated, whereby, upon release of said latch prior to discharge said receptacle and contents will be automatically inverted through the action of gravity to produce remixing of the constituents of the mixture. 115

5. In a mobile vehicle for transporting mixed concrete and like mixtures embodying segregatable constituents of different specific 120 gravities, a chassis; a closed unbalanced receptacle having circular trackways freely 125 rotatably mounting it on said chassis with its center of gravity displaced from its axis of rotation; and a latch for releasably holding said receptacle and its contents during transport with the heavier portion elevated, whereby, upon release of said latch prior to discharge said receptacle and contents will be automatically inverted through the action of gravity to produce remixing of the constituents of the mixture. 130

gravities, a chassis; a closed elongated receptacle of irregular substantially semi-circular cross section rotatably pendulously mounted on said chassis, one wall of said receptacle being formed to assist in a re-mixing action; and a latch for releasably holding said receptacle and its contents during transport with the heavier portion elevated, whereby

upon release of said latch prior to discharge said receptacle and contents will be automatically inverted through the action of gravity to produce re-mixing of the constituents of the mixture.
